UNITED STATES PATENT OFFICE

2,088,827

PERMANENT WAVE SPACER AND PROTECTOR

Clark W. Wilson, Kansas City, Mo., assignor of
one-third to Leora Love, Kansas City, Mo.

Application May 21, 1936, Serial No. 80,998

16 Claims. (Cl. 132—36.1)

This invention relates to hair waving equipment and particularly an unique spacer and protector for permanent wave machines, and the primary object of the invention is to provide such a device that may be used in connection with either "machine" or "machineless" permanent waving equipment.

It is now well known in the art that permanent waves may be imparted to the hair through the use of appliances employing clamps, wherein is embodied electrical heating elements or the like for imparting heat to the wound strand of hair and further that the heat required may be obtained through the use of chemical pads which are utilized in giving what is known in the trade as machineless waves.

In either instance, there must be provided a spacer and protector in the form of a clamp, which not only serves to hold the wound tress in place to receive heat, but functions to protect the scalp of the patron during the time heat is being applied.

Heretofore clamps have incorporated specific structure for employing the aforesaid chemical pads, but said structure invariably precluded the use of the clamp when a "machine" wave was being given.

Besides the broad primary object of the invention above set down, the same includes other objects that relate to specific structure which permit embodying in a permanent wave spacer and protector, means for adapting it for use when giving either one of the two aforementioned types of permanent waves.

Such minor, yet important, objects of the invention will appear during the course of the specification, referring to the accompanying drawing, wherein:

Figure 1 is a top plan view of a permanent wave spacer and protector made in accordance with the present invention.

Fig. 2 is a side elevation of the same.

Fig. 3 is an end view of the device.

Fig. 4 is an end elevation of the other end of the device.

Fig. 5 is a top plan view of the spacer and protector, showing the same open and without spool or pad.

Fig. 6 is an enlarged, detailed, cross sectional view through the spacer and protector.

Fig. 7 is a fragmentary, detailed, cross sectional view through the same, taken on line VII—VII of Fig. 1, and,

Fig. 8 is a stretch-out view, illustrating the

removable sheet of resilient material and associated parts.

It is customary in spacers and protectors of the general character embodying this invention, to include therein a pair of bars 10 and 12 respectively, and these bars are hingedly interconnected at one end so that they may be spread apart to receive the tress therebetween. End wall 14 in this instance serves as the means for hingedly interconnecting bars 10 and 12. This end wall has a pair of inturned ears 16 and an inturned lip 18, between which bars 10 and 12 are secured by transverse rivets 20. Wall 14 has an arcuate notch 22 formed therein that serves as one bearing for the conventional type spool 24, upon which the tress is wound during the permanent waving operation.

The opposite ends of bars 10 and 12 are normally latched together and means is provided for releasably locking the bars in the closed position. In this instance there is a wall 26, turned inwardly as at 28, along the bottom thereof, to engage bars 10 and 12. A plate 30 is disposed below bars 10 and 12 and serves as a guide for the free end of bar 12 during manipulation of the same. A rivet 32 pivotally mounts wall 26 and associated parts upon the end of bar 10 and a latch lever 34 is pivotally mounted as at 36 between 28 and 30. Latch lever 34 has a laterally extending element 38 that engages in notch 40, formed on bar 12, and moving lever 34 about pivotal connection 36 will readily draw bar 12 into engagement with opposed bar 10 so that the tress may be clamped in position. Wall 26 is notched as at 42 to receive the conventional squared end 44 of spool 24.

Clamps made as just above set down are somewhat common in the art and there is associated with such clamps, means for holding chemical pads when machineless permanent waves are being given. This invention contemplates structure which will permit the clamps to be used in any instance and, therefore, the unique parts associated with the elements just above mentioned become important.

To carry out the invention, bars 10 and 12 have formed thereon adjacent each end respectively and at the longitudinal edges thereof, ears 46 and lugs 48. Ears 46 are preferably arched as shown in Figs. 6 and 7 and the inner faces of lugs 48 should be flat for the purpose herein-after disclosed.

A detent 49 struck from each of said bars respectively forms a bearing for sheet and rod 52 and 56 respectively when pressure is applied

and there is a tendency on the part of rod 56 to longitudinally spring.

Each bar respectively has associated therewith, a specially constructed plate 50 that is secured to one longitudinal edge of a sheet of resilient material 52. In practice, this material is sheet rubber and plate 50 is rebent upon itself along one longitudinal edge to present a marginal portion 54 that will engage a similar portion of sheet 52. 10 The opposite longitudinal edge of plate 50, therefore, is swingable toward and from one face of sheet 52. The other longitudinal edge of sheet 52 has means associated therewith for removably affixing the sheet to the inner longitudinal edge of 15 the respective bar. In the instance illustrated, a rod 56, having sheet 52 curled therearound, affords such means and the ends of rod 56 project beyond the ends of sheet 52.

Reference to Fig. 8 will readily indicate the 20 manner in which plate 50 likewise projects beyond the ends of sheet 52. Rod 56 has flattened faces formed on the projected portions thereof, and when plate 50 is moved to position, these flattened faces are moved against the flat inner sides of 25 lugs 48. From this point of attachment along the inner longitudinal edge of the associated bar, sheet 52 is carried across the said inner longitudinal edge to face the same and thence along the bottom or one side of the bar to the other 30 longitudinal edge. From this line, sheet 52 is carried upwardly so that one edge of plate 50 rests upon a portion of the bar immediately adjacent the arched, upturned ears 46. The free longitudinal edge of plate 50 is cut away as shown in 35 dotted lines of Fig. 8 to allow this assembly and extended portions of plate 50 in one instance to rest against the edge of members 16 so as to preclude inward movement of the lower longitudinal edge of plate 50. Obviously, sheet 52, extending 40 upwardly between the bar and plate 50 substantially throughout the length of the plate, will further assist in this holding action.

When the parts are so assembled, plate 50, which is transversely arched, will be in an 45 upstanding position as illustrated in the figures of the drawing. Each bar will have a plate 50 along the outer longitudinal edge thereof and, therefore, a pad 58 will be held in place so that it is 50 wound.

When pad 58 is not to be used, but a clamp is 55 to be secured against the wound tress, plates 50 are merely swung down to a position substantially against and in parallel relation with their associated bars. In this position, plates 50 will not interfere with spool 24 and they will remain in such place without dislocation throughout the entire waving operation. The resiliency of sheet 52 serves to hold plate 50 in position and plate 50 is 60 fulcrumed about a portion of its lower longitudinal edge when it is moved inwardly to the inoperative position.

Removal of the unit illustrated in Fig. 8 is easy 65 and replacement may be accomplished expeditiously. The portion of sheet 52 along the inner longitudinal edge of the bars serves to present a face which will yield when bars 10 and 12 are drawn together to the end that the tress is securely clamped.

70 A vast number of advantages will be apparent to one skilled in the art after an understanding of this invention, and while the preferred embodiment thereof has been illustrated and described, it is desired to be limited only by the scope of 75 the appended claims.

Having thus described the invention, what is claimed as new and desired to be secured by Letters Patent is:

1. A permanent wave spacer and protector comprising a pair of bars; means interconnecting 5 said bars for movement toward and from each other where the longitudinal edge of one bar is abutting a longitudinal edge of the other bar; an upstanding plate along the other longitudinal edges of each bar respectively; and a sheet of 10 resilient material in connection with each plate respectively to yieldably maintain the same in operative position, said sheets of material each extending across one side of the respective bars and across the abutting edges thereof to present yieldable 15 faces for the said abutting edges.

2. A permanent wave spacer and protector comprising a pair of bars; means interconnecting 20 said bars for movement toward and from each other where the longitudinal edge of one bar is abutting a longitudinal edge of the other bar; an upstanding plate along the other longitudinal edges of each bar respectively; a sheet of resilient material in connection with each plate respectively to yieldably maintain the same in operative 25 position, said sheets of material each extending across one side of the respective bars and across the abutting edges thereof to present yieldable faces for the said abutting edges; bearings carried by the bars at the ends thereof; and a spool 30 journaled in said bearings above the abutting edges of said bars.

3. A permanent wave spacer and protector comprising a pair of bars; means interconnecting 35 said bars for movement toward and from each other where the longitudinal edge of one bar is abutting a longitudinal edge of the other bar; an upstanding plate along the other longitudinal edges of each bar respectively; and a sheet of resilient material in connection with each plate respectively to yieldably maintain the same in operative position, said sheets of material each extending 40 across one side of the respective bars and across the abutting edges thereof to present yieldable faces for the said abutting edges, said bars 45 having means for releasably latching the same together with the yieldable faces of the abutting edges in compressed condition.

4. In a permanent wave spacer and protector 50 having a pair of bars interconnected for movement toward and from each other, bearings carried by the bars, and a spool journaled in said bearings, the combination of a sheet of resilient material extending partially around each bar respectively, each sheet of material having a 55 plate along one edge thereof and means along the opposite edge for releasably engaging the bar, said plate being yieldably held in an upstanding position by said sheet.

5. In a permanent wave spacer and protector 60 having a pair of bars interconnected for movement toward and from each other, bearings carried by the bars, and a spool journaled in said bearings, the combination of a sheet of resilient material extending partially around each bar respectively, each sheet of material having a plate 65 along one edge thereof and means along the opposite edge for releasably engaging the bar, said plate being yieldably held in an upstanding position by said sheet, said sheet of material and plate being readily removable as a unit from the bar.

6. In a permanent wave spacer and protector having a pair of bars interconnected for movement toward and from each other, bearings car- 75

ried by the bars, and a spool journalled in said bearings, the combination of a sheet of resilient material extending partially around each bar respectively, each sheet of material having a plate along one edge thereof and means along the opposite edge for releasably engaging the bar, said plate being yieldably held in an upstanding position by said sheet, said sheet of material extending across one side of the bar 10 and over one edge thereof to serve as a protecting element and clamp facing respectively.

7. In a permanent wave spacer and protector having a pair of bars interconnected for movement toward and from each other, bearings carried by the bars, and a spool journalled in said bearings, the combination of a sheet of resilient material extending partially around each bar respectively, each sheet of material having means at one longitudinal edge thereof for engaging one 20 side of the associated bar at one edge thereof, and a plate secured along the opposite longitudinal edge engageable with ears provided on the associated bar on the same side at the other edge thereof, said sheet of material being under 25 tension whereby to yieldably hold the said plate in an upstanding position.

8. In a permanent wave spacer and protector having a pair of bars interconnected for movement toward and from each other, bearings carried by the bars, and a spool journalled in said bearings, the combination of a sheet of resilient material extending partially around each bar respectively, each sheet of material having means at one longitudinal edge thereof for engaging 30 one side of the associated bar at one edge thereof, and a plate secured along the opposite longitudinal edge engageable with ears provided on the associated bar on the same side at the other edge thereof, said sheet of material being under 35 tension whereby to yieldably hold the said plate in an upstanding position, said plate being swingable from the upstanding position to a position substantially parallel with and against the said one side of the bar.

45 9. In a permanent wave spacer and protector having a pair of bars interconnected for movement toward and from each other, bearings carried by the bars, and a spool journalled in said bearings, the combination of a sheet of resilient material extending partially around each bar respectively, each sheet of material having means at one longitudinal edge thereof for engaging one side of the associated bar at one edge thereof, and a plate secured along the opposite longitudinal edge engageable with the ears provided on the associated bar on the same side at the other edge thereof, said sheet of material being under tension whereby to yieldably hold the said plate in an upstanding position, said 50 sheet of material extending across the other side of said bar when the rod and plate are in engagement with the lugs and ears respectively.

10. In a permanent wave spacer and protector having a pair of bars interconnected for movement toward and from each other, bearings carried by the bars, and a spool journalled in said bearings, the combination of a sheet of resilient material extending partially around each bar respectively, each sheet of material having means 55 at one longitudinal edge thereof for engaging one side of the associated bar at one edge thereof, and a plate secured along the opposite longitudinal edge engageable with ears provided on the associated bar on the same side at the other edge thereof, said sheet of material being under 60

tension whereby to yieldably hold the said plate in an upstanding position, said plate being transversely arched whereby to cause the upper edge thereof to overhang the supporting bar.

11. In a permanent wave spacer and protector having a pair of bars interconnected for movement toward and from each other, bearings carried by the bars, and a spool journalled in said bearings, the combination of a sheet of resilient material extending partially around each bar respectively, each sheet of material having means at one longitudinal edge thereof for engaging one side of the associated bar at one edge thereof, and a plate secured along the opposite longitudinal edge engageable with ears provided on the associated bar on the same side at the other edge thereof, said sheet of material being under tension whereby to yieldably hold the said plate in an upstanding position, the ears serving to preclude accidental swinging of the plate outwardly from the side of the associated bar.

12. In a permanent wave spacer and protector having a pair of bars interconnected for movement toward and from each other, bearings carried by the bars, and a spool journalled in said bearings, the combination of a sheet of resilient material extending partially around each bar respectively, each sheet of material having means at one longitudinal edge thereof for engaging one side of the associated bar at one edge thereof, and a plate secured along the opposite longitudinal edge engageable with ears provided on the associated bar on the same side at the other edge thereof, said sheet of material being under tension whereby to yieldably hold the said plate in an upstanding position, said plate being swingable in one direction from the upstanding position to a position substantially parallel with the said one side of the bar, one edge of said plate bearing upon the said side of the bar and 40 serving as a fulcrum during such swinging movement.

13. In a permanent wave spacer and protector having a pair of bars interconnected for movement toward and from each other, bearings carried by the bars, and a spool journalled in said bearings, the combination of a sheet of resilient material extending partially around each bar respectively, each sheet of material having means at one longitudinal edge thereof for engaging one side of the associated bar at one edge thereof, and a plate secured along the opposite longitudinal edge engageable with ears provided on the associated bar on the same side at the other edge thereof, said sheet of material being under tension whereby to yieldably hold the said plate in an upstanding position, said plate being swingable in one direction from the upstanding position to a position substantially parallel with the said one side of the bar, one edge of said plate bearing upon the said side of the bar and serving as a fulcrum during such swinging movement, said ears serving to preclude swinging of the plate in the opposite direction.

14. In a permanent wave spacer and protector having a pair of bars interconnected for movement toward and from each other, bearings carried by the bars, and a spool journalled in said bearings, the combination of a sheet of resilient material extending partially around each bar respectively, each sheet of material having a rod attached along one longitudinal edge thereof for engaging behind lugs provided on one side of the associated bar at one edge thereof, and a plate secured along the opposite longitudinal edge en-

gageable with ears provided on the associated bar on the same side at the other edge thereof, said sheet of material being under tension whereby to yieldably hold the said plate in an upstanding position.

5. 15. In a permanent wave spacer and protector having a pair of bars interconnected for movement toward and from each other, bearings carried by the bars, and a spool journaled in said 10 bearings, the combination of a sheet of resilient material extending partially around each bar respectively, each sheet of material having a rod attached along one longitudinal edge thereof for engaging behind lugs provided on one side of the associated bar at one edge thereof, and a 15 plate secured along the opposite longitudinal edge

engageable with ears provided on the associated bar on the same side at the other edge thereof, said sheet of material being under tension whereby to yieldably hold the said plate in an upstanding position, said bar having flat faces formed thereon for engaging the lugs to preclude dislodgement from the operative position.

5. 16. In a permanent wave spacer and protector of the character described, having a clamp, a pair of opposed, upstanding rigid plates on the clamp, 10 independently swingable to and from an operative position in parallel, spaced-apart relation, and resilient means for maintaining the plates in the operative position forming, with the clamp, an open channel for the purpose specified. 15
